UNITED STATES PATENT OFFICE

WILLIAM C. DEVEREAUX, OF DETROIT, MICHIGAN, ASSIGNOR TO FERRO STAMPING & MANUFACTURING COMPANY, OF DETROIT, MICHIGAN, A CORPORATION OF MICHIGAN

REMOTE CONTROL MECHANISM FOR DOOR LATCHES

Application filed January 23, 1928. Serial No. 248,752.

This invention relates generally to vehicle door latches and consists of certain novel features of construction, combinations and arrangements of parts as will be hereinafter more fully described and particularly pointed out in the appended claims.

In the accompanying drawings:

Figure 1 is a side elevation of a latch mechanism embodying my invention showing the parts in dogging position and dotted in neutral position;

Figure 2 is a view similar to Figure 1 and showing the parts in bolt retracting position;

Figure 3 is a sectional view taken on the line 3—3 of Figure 1;

Figure 4 is a sectional view taken on the line 4—4 of Figure 1;

Figure 5 is a sectional view taken on the line 5—5 of Figure 1;

Figure 6 is a sectional view taken on the line 6—6 of Figure 1;

Figure 7 is a rear elevation of a portion of the case plate, showing the key-hole slot;

Figure 8 is a perspective view.

Referring now to the drawings, 1 is a case plate adapted to be secured to the inner side of a door and having a lateral flange 2 at its forward edge adapted to be secured to the free edge of the door, 3 is a reciprocating bolt that is movable through an opening 4 in the lateral flange 2 for engagement with a suitable keeper (not shown), 5 is a substantially flat yoke rigidly secured to the bolt 3 and adapted to slide on the case plate 1 between struck out lugs 6, 7 is a helical spring anchored on the case plate and having a depending arm 8 abutting a shoulder 9 of the yoke 5 and normally retaining the bolt 3 in projected position, and 10 is a rotatably mounted rollback that is operable from the outside of the door by the shank 11 of a suitable handle (not shown) to engage an arm 12 of the yoke 5 to effect a retraction of the bolt 3 against the tension of the spring 7.

In the present instance the yoke 5 is retained on the case plate 1 between the guide lugs 6 by means of a headed stud 13 that projects laterally from the body of the yoke and engages a key hole slot 14 in the case plate 1. Preferably this slot 14 is spaced

from the lateral flange 2 so that the shank 15 of the stud 13 on the yoke will normally be in the narrow elongated portion 16 of the slot when the parts are assembled and in operative position, but may be received in the circular portion 17 of said slot either before the roll back 10 is mounted in place or after it has been removed from the case plate.

For retracting the bolt 3 from the inner side of the door I have provided a lever 18 that is swingingly mounted on the inner side of the door at a point remote from the case plate 1 and that is operatively connected to the yoke 5 by suitable links 19 and 20. As shown, the lever is non-rotatably secured to a stub shaft 21 journaled in an auxiliary case plate 22 and cover plate 23, and is adapted to be actuated from the inner side of the door by means of a suitable handle 24 that is secured to the stub shaft 21 at the inner end thereof. The upper end of this lever 18 is pivotally connected to the rear end of the link 19 and the forward end of the latter is detachably connected to the rear end of the link 20 which in turn is slidably mounted on and has lost motion connections with the yoke 5. Preferably the link 19 has an elongated slot 25 at its forward end receiving a laterally projecting substantially T-shaped tongue 26 at the rear end of the link 20. A lug 27 projects laterally from the link 20 at the proper distance from the tongue 26 to constitute a stop for the forward end of the link 19, and a tongue 28 projects laterally inwardly and forwardly from the rear end of the slot 25 and overlaps the outer free edge of the T-shaped tongue 26 so as to yieldably retain the tongue in the slot 25. The link 20 has two aligned longitudinally spaced elongated slots 29 and 30 respectively that receive the shanks 31 and 32 of headed studs 33 and 34 projecting laterally from the yoke 5, and is provided at its forward end with a forward extension or projection 35 for engagement with a shoulder 36 of the roll back 10 to render the latter inoperative for retracting the bolt. Preferably the arrangement of the slots 29 and 30 and the studs 33 and 34 is such that the stud shanks 31 and 32 will engage the forward ends of the slots 100

29 and 30 when the link 20 is moved rearwardly from neutral position by the link 19 and lever 18 to retract the bolt, but will permit the link 20 to slide forwardly past neutral position to cause the projection 35 5 to operatively engage the shoulder 36 of the roll back 10 when the link 19 and lever 18 are swung forwardly to dog the roll back. Thus the link 20 constitutes a portion of the inside bolt retracting means and has a portion 10 that constitutes a dog for the roll back 10. Any suitable means such as the coil spring 40 and washer 41 sleeved on the stud shank 31, and the spring metal spider 42 surrounding the stub shaft 21 between the lever 18 and auxiliary case plate 22 may be used to detachably hold the links 19 and 20 in the several adjusted positions just mentioned.

15 While it is believed that from the foregoing description, the nature and advantage of my invention will be readily apparent, I desire to have it understood that I do not limit myself to what is herein shown and described 20 and that such changes may be resorted to 25 when desired as fall within the scope of what is claimed.

What I claim as my invention is:

1. In a latch, the combination with a case 30 plate having a key hole slot therein, and a latch bolt carried by said case plate, of a yoke connected to the latch bolt and slidable over one face of said case plate, and connections between said yoke and case plate including an element projecting from said yoke and engaging said key hole slot, the arrangement being such that the said member is in the narrow elongated portion of said slot.

2. In a door latch, the combination with a 40 latch bolt, and a yoke connected thereto, of means for retracting said bolt including a pair of links, studs projecting from said yoke and having a slotted connection with one of said links, and a tongue projecting from one of said links and having a slotted connection with the other of said links.

3. In a door latch, the combination with a latch bolt, and a yoke connected thereto, of 50 means for retracting said bolt including a link connected to said yoke, having a tongue projecting laterally therefrom, and a lug projecting laterally therefrom in spaced relation to said tongue, and a second link having a slot receiving said tongue and having an end 55 abutting said lug.

4. In a latch, the combination with a case plate, a spring pressed latch bolt yoke movable over the case plate, and a removable rollback in advance of said yoke and adapted to 60 retract the same, of a connection between the yoke and case plate operable while the rollback is in advance of the yoke to retain the latter on the case plate and operable when the rollback is removed to permit the yoke to 65 be disconnected from the case plate.

5. In a latch, the combination with a case plate having a lateral flange at its forward edge, a latch bolt movable through the flange, a yoke on the case plate and connected to the bolt in rear of the flange, and a removable 70 rollback for retracting the bolt located between the flange and a portion of the yoke, of a connection between the yoke and case plate retaining and guiding the yoke on the case plate while the rollback is between the flange 75 and yoke but operable to permit the yoke to be disconnected from the case plate when the rollback is removed from between the flange and yoke.

6. In a door latch, a case plate, a latch bolt 80 associated with the case plate, and a yoke movable over the case plate and operable to actuate the bolt, of a connection between the yoke and case plate operable while the yoke is in certain positions relative to the case plate 85 to prevent displacement of the yoke from the case plate but operable when the yoke is in a predetermined position relative to the case plate to permit displacement of the yoke from the case plate.

7. In a door latch, a case plate, a latch bolt associated with the case plate, and a yoke movable over the case plate and operable to actuate the bolt, of a slotted connection between the yoke and case plate operable to 90 guide the yoke a predetermined distance when moved over the case plate to prevent displacement of the yoke from the case plate while being so moved, but operable when the yoke is moved beyond the predetermined distance aforesaid to permit displacement of the yoke from the case plate.

8. In a door latch, the combination with a latch bolt and a yoke connected to and constituting a rearward extension of said bolt, 105 of means for actuating the bolt including overlapping links constituting a rearward extension of the yoke, one of said links being connected to the yoke and provided at spaced points longitudinally thereof with lateral projections, and the other link having a slot receiving one and having a portion abutting the other of said projections.

9. In a door latch, the combination with a latch bolt and a yoke connected to and constituting a rearward extension of said bolt, 115 of means for actuating the bolt including overlapping links constituting a rearward extension of the yoke, one of said links being connected to the yoke and provided at spaced points longitudinally thereof with lateral projections, one of said projections being substantially T shape, and the other link having a slot receiving the T shaped projection, having a portion abutting the other projection, and having a tongue pressed therefrom, overlapping the T shaped projection and retaining the same in said slot.

10. In a door latch, the combination with a latch bolt and a yoke connected to and 130

constituting a rearward extension of said bolt, of means for actuating the bolt including overlapping links constituting a rearward extension of the yoke, one of said links being connected to the yoke and provided at spaced points longitudinally thereof with lateral projections, and the other link having a slot receiving one and having an end abutting the other of said projections, said other link also having a tongue pressed therefrom and bearing against one of the projections aforesaid.

In testimony whereof I affix my signature.

WILLIAM C. DEVEREAUX.
